[57] CLAIM

The ornamental design for a combined bottle and cap, as shown and described.

DESCRIPTION

FIG. 1 is a front elevation of a combined bottle and cap showing our new design;

FIG. 2 is a rear elevation view thereof;

FIG. 3 is a right side elevation thereof, the left side is a mirror image thereto;

FIG. 4 is a top plan view;

FIG. 5 is a bottom plan view;

FIG. 6 is a front elevation of a second embodiment of the design;

FIG. 7 is a right side elevation of the second embodiment, the left side elevation is a mirror image thereto;

FIG. 8 is a rear elevation view thereof;

FIG. 9 is a top plan view thereof;

FIG. 10 is a front elevation of a third embodiment of the design, the rear elevation is the same;

FIG. 11 is a right side elevation of the third embodiment, the left side elevation is the same;

FIG. 12 is a top plan view thereof.

FIG. 13 is a front elevation of a fourth embodiment of the design, the rear elevation is a mirror image thereto;

FIG. 14 is a side elevation view thereof.

FIG. 15 is an opposite side elevation view thereof.

FIG. 16 is a top plan view thereof.

FIG. 17 is a front elevation of the fifth embodiment of the design, the rear elevation is a mirror image thereto;

FIG. 18 is a side elevation view thereof.

FIG. 19 is an opposite side elevation view thereof; and,

FIG. 20 is a top plan view thereof.

The bottom of all of the embodiments is the same as the bottom of the first embodiment shown in FIG. 5.
